Primary Examiner — Paula Allen Greene(74) *Attorney, Agent, or Firm* — Brian M. Dingman; Dingman IP Law, PC(57) **CLAIM**

The ornamental design for a speaker, substantially as shown and described.

DESCRIPTION

FIG. 1 is a perspective view of a speaker as seen from the front, top, and right side;

FIG. 2 is top view thereof;

FIG. 3 is a bottom view thereof;

FIG. 4 is a left side view thereof;

FIG. 5 is a right side view thereof;

FIG. 6 is a rear view thereof; and,

FIG. 7 is a front view thereof.

The broken lines immediately adjacent the shaded areas represent the bounds of the claimed design while all other broken lines are directed to environment and are for illustrative purposes only; the broken lines form no part of the claimed design.

1 Claim, 4 Drawing Sheets---
